H. A. NEWHALL.
SAFETY ATTACHMENT FOR RAILROAD CARS.

No. 20,293.

Patented May 18, 1858.

Fig. 1.

Fig. 2.

UNITED STATES PATENT OFFICE.

H. A. NEWHALL, OF NEWTON, MASSACHUSETTS.

SAFETY ATTACHMENT FOR RAILROAD-CARS.

Specification of Letters Patent No. 20,293, dated May 18, 1858.

To all whom it may concern:

Be it known that I, H. A. NEWHALL, of Newton, in the county of Middlesex and State of Massachusetts, have invented a new and Improved Safety Attachment to be Applied to Railroad-Cars; and I do hereby declare that the following is a full, clear, and exact description of the same, reference being had to the annexed drawings, making a part of this specification, in which—

Figure 1, is a longitudinal vertical section of the adjoining ends of the platforms of the cars with my improvement applied to them. Fig. 2, is a plan or top view of ditto.

Similar letters of reference indicate corresponding parts in the two figures.

This invention consists in the employment or use of supplementary yielding platforms or treads constructed in a peculiar way, and used in connection with side guards, the above parts being so arranged that they may be applied to the cars and afford perfect protection to passengers in passing from one car to another while the same are in motion.

To enable those skilled in the art to fully understand and construct my invention I will proceed to describe it.

A, A, represent the adjoining ends of the platforms of two cars, and B, B, represent the usual or any proper coupling.

To the under side of each platform A, a series of metal tubes C, are placed; four are represented under each platform in Fig. 2, the tubes being shown by dotted lines, but any proper number may be used. These tubes have their ends fitted in cleats or bars D, attached to the under sides of the platforms.

In each tube C, a metal rod E, is fitted and allowed to slide freely. The inner ends of these rods bear against spiral springs a, which are placed in the tubes, and the outer ends of the rods of each platform at each side of the coupling B, B, are connected by bars b, as shown clearly in Fig. 2. The springs a, have a tendency to keep the bars b, of the two platforms in contact as shown in Fig. 2.

To the outer end of each bar b, a vertical

rod F, is attached, and to each rod F, chains G, are secured, two of which are shown attached to each rod in Fig. 1, but more may be used. These chains are attached at their opposite ends to the usual railing or guards H, of the platforms A, A, said guards extending a suitable distance from points e, in line with the rods F, toward the sides of the platforms.

From the above description it will be seen that the rods E, will yield or give to compensate for the varying width of space between the platforms, and the same may be said of the chain G, which form side guards. It is designed to have the rods E, sufficiently near together so that the feet cannot pass between them, and it will therefore be seen that passengers may pass from one car to another with perfect safety, and as the rods E, which form the treads or supplementary platforms are allowed to slide in the tubes C, and the side guards also allowed to contract or yield so that the varying width of the space between the platforms is compensated for, the device is rendered perfectly practicable.

I am aware that sliding platforms have been applied to cars and I do not claim separately and broadly such device irrespective of construction and their connection with proper side guards, but

Having thus described my invention, what I claim as new and desire to secure by Letters Patent, is—

The supplementary platforms or treads formed of the rods E, fitted in tubes C, attached to the platforms, the rods bearing against springs a, in the tubes, in combination with the side guards formed of the vertical rods F, attached to the bars b, and the chains G, which are connected to the rods F, and the railing or guards H, of the platforms, the whole being arranged substantially as and for the purpose set forth.

H. A. NEWHALL.
